United States Patent Office

Des. 177,447
Patented Apr. 10, 1956

177,447

ROADWAY STRIPE GUARD

John R. Wald, Jr., Montoursville, Pa., assignor to Wald Industries, Inc., Huntington, Pa., a corporation of Pennsylvania

Application August 4, 1955, Serial No. 37,313

Term of patent 14 years

(Cl. D72—1)

Fig. 1.

Fig. 2.

Fig. 3.

Fig. 1 is a view in perspective of the roadway stripe guard showing my new design;

Fig. 2 is a side elevational view thereof; and

Fig. 3 is an end view thereof.

I claim:

The ornamental design for a roadway stripe guard, as shown.
